UNITED STATES PATENT OFFICE.

FREDERICK W. CARPELEN, OF MINNEAPOLIS, MINNESOTA, ASSIGNOR TO DECARIE INCINERATOR COMPANY, OF MINNEAPOLIS, MINNESOTA.

INCINERATOR.

1,110,390.

Specification of Letters Patent. Patented Sept. 15, 1914.

Application filed August 2, 1912. Serial No. 712,887. Renewed May 31, 1913. Serial No. 771,082.

To all whom it may concern:

Be it known that I, FREDERICK W. CARPELEN, of Minneapolis, Hennepin county, Minnesota, have invented certain new and useful Improvements in Incinerators, of which the following is a specification.

My invention relates to domestic incinerators or that class designed for consuming the accumulation of garbage in each household.

The object of my invention is to provide an incinerator of comparatively small size adapted to be set up in the kitchen near the cook stove and connected with the gas supply and with a flue of the cook stove to the end that the waste or garbage of the household may be easily and quickly consumed and the use of garbage pails or cans entirely avoided.

20 A further object is to provide a household incinerator of simple construction and one which will present a neat, ornamental appearance in the kitchen or basement of the residence where it may be used.

25 The invention consists generally in various constructions and combinations, all as hereinafter described and particularly pointed out in the claims.

In the accompanying drawings forming 30 part of this specification, Figure 1 is a vertical sectional view of an incinerator embodying my invention, Fig. 2 is a horizontal sectional view on the line *a—a* of Fig. 1, Fig. 3 is a sectional view on the line *b—b* of Fig. 1.

In the drawing, 2 represents the wall of the incinerator, 3 a covering of non-heat conducting material, preferably asbestos, and 4 a metallic jacket for said covering. 40 5 is a filling opening in the upper portion of the incinerator wall, having a hinged door 6 which is adapted to swing outwardly, as indicated in dotted lines in Fig. 1, to expose said opening and form a slide over 45 which the material to be incinerated is discharged into the incinerating chamber.

7 represents the incinerating chamber, having a flue opening 8 leading to a suitable exhaust flue for the products of combustion and gases, not shown. Where the incinerator is located in the kitchen, it is preferably placed beside the gas stove or range and the flue opening 8 is connected with the chimney in any suitable manner.

55 9 is a grate, located at the bottom of the

incinerating chamber near an opening 10 provided with a door 11 through which inspection may be had of the grate and the contents of the chamber. The grate is provided with a central opening 12 but in other respects corresponds to an ordinary fire grate composed of bars suitably spaced apart. Above the central opening in the grate is a hood 13, preferably circular in form, open at the top and bottom and supported by any suitable means, such as bars 14. The lower end 15 of the hood is preferably flared or bell-shaped and is spaced a suitable distance from the grate and the central opening therein 70 and the walls of the hood are preferably provided with a series of holes 16 and baffle plates 17 are also preferably provided within the hood, projecting from the walls thereof inwardly toward the center of the hood. These baffle plates are in staggered relation to one another and operate to deflect the products of combustion and gases from one side of the hood to the other. When the material is deposited in 80 the incinerating chamber it will contact with the walls of the hood and be deflected outwardly thereby upon the grate, and the bell shaped lower end of the hood will prevent the material to be consumed from accumulating on the middle portion of the grate and clogging the central draft opening therethrough. The hood will also operate to preserve a central draft opening upwardly through the mass of material and 85 prevent it from choking the draft, even though it may be wet and have a tendency to pack down upon the grate. The holes in the walls of the hood will also allow the hot gases and flames from the burning material 90 beneath to work outwardly through the mass of garbage and aid in drying the same and hasten the incinerating operation.

Beneath the grate 9 I provide a chamber 18 which I prefer to designate as the burner chamber, in the bottom of which is an auxiliary grate 19 with its bars preferably in staggered relation to the bars of the grate 9, an opening 20 being provided in the wall of the incinerator, normally closed by a door 21 through which access may be had to the burner chamber.

At intervals in the walls of the burner chamber I provide a gas burner 22 having a hood 23 at its lower end through which 130

air is admitted to the burner and into which hood a gas supply pipe 24 extends, forming, in effect, a Bunsen burner, the air and gas being mixed at the point where the gas supply pipe enters the hood. The nozzle of this burner is preferably located near the grate 9 and the flame will be directed inwardly under the grate and up through the bars thereof, and the material on the grate will be thoroughly and quickly consumed. Any suitable number of the burners may be provided around the walls of the burner chamber and when the gas discharged into the chamber is ignited the incinerating chamber will be raised to a high temperature and the garbage therein will be thoroughly dried and consumed.

Beneath the grate 19 is an ash chamber 25, having an opening 26, a door 27 and auxiliary burners 28 in its walls. These auxiliary burners operate to heat the grate 19 and consume any material that may fall on this grate from the grate above.

I claim as my invention:

1. An incinerator comprising a casing having a chamber provided with a filling opening and a flue leading therefrom, a grate disposed in the lower portion of said incinerating chamber and having a central opening, a hood disposed above said opening and having holes in its walls, the lower end of said hood being spaced from said grate and flared or bell-shaped to direct the material away from said opening, and gas burners extending through said casing beneath said grate.

2. An incinerator comprising a casing having an incinerating chamber provided with a filling opening and a flue for the products of combustion, a grate arranged in the lower part of said incinerating chamber and having an unobstructed central opening leading from the space beneath said grate to said incinerating chamber, and a hood supported above said unobstructed opening and spaced therefrom and having a series of holes in its walls, said hood being adapted to deflect the material discharged into said incinerating chamber outwardly, away from said opening.

3. An incinerator comprising a casing having an incinerating chamber provided with a filling opening and a flue for the products of combustion, a grate arranged in the lower part of said incinerating chamber and having an opening therethrough, a hood supported above said grate opening and operating to direct the material laterally, away from said opening, and a series of burners arranged in the wall of said casing beneath said grate and adapted to direct the flames inwardly toward said central opening and horizontally with respect to said grate.

4. An incinerator comprising a casing having an incinerating chamber provided

with a filling opening and a flue for the products of combustion, a grate arranged in the lower part of said incinerating chamber and having a central opening, a hood supported above said central opening and spaced therefrom and having a series of holes in its walls, and baffle plates provided in said hood and projecting partially across the same in staggered relation to one another.

5. An incinerator comprising a casing having an incinerating chamber provided with a filling opening and a flue for the products of combustion, a grate disposed in the lower part of said incinerating chamber and having a central unobstructed opening, an elongated hood, cylindrical in form, supported above the opening in said grate and spaced therefrom and open at each end, the walls of the lower end of said hood flaring outwardly to direct the material falling thereon to the outer portions of the grate, said hood extending upwardly above the lower portions of said filling opening and the walls of said hood having a series of holes therein and gas burners arranged to direct flames horizontally beneath said grate and upwardly through the bars thereof.

6. An incinerator comprising a casing having a chamber provided with a filling opening and a flue leading therefrom, a grate disposed in the lower portion of said incinerating chamber and having a central unobstructed opening, means supported above said grate and spaced from said central opening and adapted to direct the material falling toward said opening outwardly to the sides of said grate, and a series of burners projecting through the wall of said casing at intervals around said grate and directing the flames horizontally toward said central opening.

7. An incinerator comprising a casing having an incinerating chamber provided with a filling opening and a flue for the products of combustion, a grate arranged in the lower part of said incinerating chamber and having an opening therethrough, a hood supported above said grate opening and spaced therefrom and operating to direct the material laterally, away from said opening, and a series of burners arranged beneath said grate and adapted to direct the flames inwardly toward said opening.

8. An incinerator comprising a casing having an incinerating chamber provided with a filling opening and a flue for the products of combustion, a grate arranged in said incinerating chamber and having an opening therethrough, means arranged above said opening and spaced therefrom for directing the material laterally on said grate, away from said opening, and a series of burners mounted below said grate at intervals around the same and arranged to direct the

flames inwardly toward said opening and radially with respect to said grate and adjacent thereto.

9. An incinerator comprising a casing 5 having a chamber provided with a filling opening and a flue leading therefrom, a grate disposed in the lower portion of said chamber and having a central, unobstructed opening, means spaced from said grate for 10 deflecting the material laterally, away from said opening, and a plurality of gas burners disposed beneath said grate and directing the flames radially with respect to said grate toward said opening and adjacent to the 15 bars of said grate.

10. An incinerator comprising a casing having a chamber provided with a filling opening and a flue leading therefrom, a grate disposed in said chamber, means supported above said grate and spaced therefrom for deflecting the material laterally toward the sides of said grate, the portion of the grate beneath said deflecting means having an unobstructed opening therein, and a 25 plurality of burners arranged below said grate and arranged to direct the flames inwardly beneath and adjacent to the bars of said grate and toward said unobstructed opening.

30. 11. An incinerator comprising a casing having an incinerating chamber provided with a filling opening and a flue for the products of combustion, a grate arranged in the lower part of said incinerating chamber, a hood supported above said grate and having a series of holes in its walls, and baffle plates provided in said hood and projecting partially across the same and operating to direct the products of combustion 35 from side to side in said hood.

40. 12. An incinerator comprising a casing having an incinerating chamber provided with a filling opening and a flue for the products of combustion, a grate arranged in the lower part of said incinerating chamber 45 and having a central opening therein, a hood supported above said central opening and having an open lower end, and a series of holes in its walls, and baffle plates provided 50 within said hood and projecting partially across the same and compelling the products of combustion to follow a tortuous path in said hood.

55. 13. An incinerator comprising a casing having an incinerating chamber provided with a filling opening and a flue for the products of combustion, a grate disposed in the lower part of said incinerating chamber,

a hood supported above said grate and open at each end, the wall of the lower portion 60 of said hood directing the material to the outer portions of the grate, the walls of said hood having a series of holes therein, and means within said hood for compelling the products of combustion to follow a tortuous path therein.

14. An incinerator comprising a casing having an incinerating chamber provided with a filling opening and a flue for the products of combustion, a grate disposed in 70 the lower part of said incinerating chamber and having a central opening therein, means supported above said opening and spaced from said grate and operating to deflect the material to the sides of said grate and away 75 from said opening, said means having an opening therethrough for the products of combustion and preventing the material to be consumed from entering and clogging said grate opening.

80. 15. An incinerator comprising a casing having an incinerating chamber provided with a filling opening and a flue for the products of combustion, a grate disposed in the lower part of said incinerating chamber, 85 a hood supported above said grate and spaced therefrom and having a series of comparatively small holes in its side walls sufficient to allow the passage of the products of combustion and too small to permit 90 the passage of the material to be consumed, the lower end of said hood operating to deflect the material outwardly to the sides of said grate.

16. An incinerator comprising a casing 95 having an incinerating chamber provided with a filling opening and a flue for the products of combustion, a grate disposed in the lower part of said incinerating chamber, a hood arranged above said grate and spaced 100 therefrom and having openings therein for the passage of the products of combustion, said openings being too small to allow the entrance of the material to be consumed, the lower portion of said hood separating 105 the mass of material and permitting the products of combustion and the flames to pass therethrough, and burners arranged to direct the flames through said grate adjacent to the lower end of said hood.

110. In witness whereof, I have hereunto set my hand this 17th day of July, 1912.

FREDERICK W. CAPPELEN.
